UNITED STATES PATENT OFFICE

DAVID BAUM, OF LIVERMORE FALLS, MAINE

GLOVE-TURNING MACHINE

Application filed February 20, 1928, Serial No. 255,688. Renewed November 15, 1929.

My invention relates to improvements in glove turning machines in which plungers and tubular glove supports are employed in reversing the glove, from right side to wrong side, or vice versa.

A glove turning machine patented by me on July 27, 1920, No. 1,348,077, involving the use of these co-acting members, was provided with but one glove thumb support, this element being swung from one side to the other of the line of finger supports to serve in turning right and left hand gloves, respectively.

In operating these machines with the single glove thumb support the uncertainty of accurately aligning the support with the plunger and holding it in alignment while the glove is being operated on is always present, and it is one of the objects of my present invention to provide a remedy for this trouble.

I employ for this purpose a bifurcated glove thumb support carrier which straddles the line of finger supports, and mount on each branch of the carrier a glove support. By swinging the carrier in either direction, so as to bring one of the supports into alignment with its respective and mating plunger, I am able to turn, alternately, both right and left hand gloves.

I am aware of the fact that others have incorporated in their glove turning machines the general idea of duplex glove thumb supports, but, so far as I have knowledge, both of these supports have been fixed in operative position on the machine, one on each side of the line of finger supports and in close relation thereto, and the support which is not in use at the time is so close to the finger supports that it greatly inconveniences the operator in placing the glove over the five operating supports, and often this is not accomplished without including the inoperative thumb support,— with a consequent delay in replacing the glove over the proper supports.

My construction contemplates manual rotation of the carrier to alternately bring one thumb support into and remove the other out of operative position, which ar-

rangement provides more space between the inoperative thumb support and the line of finger supports for the operator to locate the glove than would be the case were both thumb supports immovable fixtures on the machine.

An important object is to provide automatic means, supplementing the manual actuation of the carrier, to insure a final correct alignment of the co-acting members before they actually and mutually engage, a provision made necessary on account of the fact that the operator might unintentionally neglect to place the support in its proper relation to the plunger.

And a further object of the invention is to provide, in conjunction with the aligning feature, certain arrangements of the parts to procure a safety mechanism, through the use of which it will be practically impossible to manually position either of the glove thumb supports so that accidental interference can take place between the support and plunger when the latter descends.

For the purpose of illustrating my invention I have prepared the accompanying drawings in which is disclosed one embodiment which, at the present time, I consider preferable to other possible forms in which the invention might be carried out.

In these drawings,—

Fig. 1 is a fragmentary side elevation of certain parts of a glove turning machine, the elements of my invention being shown thereon;

Fig. 2 is a plan view of the same;

Fig. 3 is a plan view of the carrier and also the several supports and plungers;

Fig. 4 is a plan view of the carrier and the aligning plunger assembly;

Fig. 5 is a section taken on line 5—5, Fig. 4, and

Fig. 6 is a section taken on line 6—6, Fig. 2, showing means for securing the thumb support to the carrier.

Similar characters of reference identify like parts in all views.

In the drawings, wherein is shown so much only of my former glove turning ma-

chine as will comprehensively connect the present invention therewith, 1 is the column, 2 the fixed bracket, and 3 the vertically movable bracket of my former invention.

5 Fixed on the bracket 2 are the finger supports 4 and adjustably secured to the bracket 3 are the finger plungers 5. The bracket 3 may be reciprocated on the column 1 by any convenient means, as for instance 10 that shown in my former patent hereinbefore referred to.

Secured to the bracket 3 and reciprocable therewith is a bar 6 and pivoted on the column 1, at 7, is a swinging arm 8, 15 journaled on which at 9 is a roll 10. An offset portion 11 carries a helical spring 12 which normally holds the arm 8 against the column at the abutting point 13.

Referring to Fig. 2, 14 is a bifurcated or 20 forked member which I call a carrier, and at the end of each fork thereof is removably and adjustably secured a glove thumb support 15, each support being adaptable of alignment with its adjacent plunger 16.

25 The carrier is pivotally secured to the bracket 2 by the pin 17 and its extreme rotary movements on the bracket in either direction are restricted by the adjustable stop screws 18.

30 On a central line through the carrier and journaled near the apex thereof is a roll 19 which is always in engagement with the wedge-shaped end of the ram 20, the latter being slidably mounted in the bearing 21.

35 Within the bore 22 of the ram is a compression spring 23, one end of which seats at the bottom of the bore and the other end abuts on the head 24 of the plunger 25. A collar 26 acts to retain the plunger with- 40 in the bore of the ram.

On the lower end of the pin 17 is a crank arm 27 with its forked end making connection with the connecting-rod 28. This member 28, when provided with the proper 45 facilities for operating, such, for instance, as I adopted for a similar element in my former patented machine, is employed by the machine tender to manually actuate the carrier so as to position one or the other 50 of the two thumb supports in at least approximate alignment with its mating plunger.

Reverting to Fig. 1, it will be observed 55 that the arm 8 is delineated in both full and dot-and-dash lines. The former position represents the arm in its normal, inert position.

On the downward stroke of the bracket 3, the bar 6, engaging the roll 10, will cause 60 the arm 8 to move to the position shown in dot-and-dash lines, this action swinging the lower end of the arm against the plunger 25 and forcing the ram 20 outwardly into strong engagement with the roll 19, and this 65 engagement will occur regardless of the po-

sition in which the carrier may be at the time.

In another patent issued to me on May 12, 1925, numbered 1,537,794, having to do with glove thumb and finger supports, these elements were made with expandable tops. 70

In glove turning it is desirable, when using expandable top supports, to have the line of expansion of the thumb support disposed at a slight angle with the line cutting the centers of all the finger supports, and it is, of course, essential that this angle be similar in both thumb supports. 75

In Fig. 3 I have shown, diagrammatically, the direction of expansion of the tops of the supports 15, as on line *a*—*a*, and the angle between the line of expansion and the central line through the finger supports as indicated by *b*. 80

In my earlier machine, in which a single thumb support was swung from one side to the other of the central line *c*—*c*, the angle *b* was dissimilar in the two positions, but with my present construction it is obvious that not only similar angles for the two supports can easily be provided for, but that various different angles *b* to suit varying conditions in the grade or style of the glove may be obtained by adjusting the supports on the carrier. 85

In Fig. 4 I illustrate a condition which might possibly, although not probably occur in operating the glove turning machine. In this instance the operator has manually swung the carrier over from one side toward the other and left it on exactly the central line,—or in other words the ram 20 and the roll 19 are in alignment with the pivotal point 17 of the carrier, which brings the carrier to a "dead center" line. If the carrier should remain in this position during a downward stroke of the bracket 3, the plungers 16 would not register with the supports 15 and the thumb of the glove would not be turned. But no damage to the machine or any of its parts could occur as all 100 that would take place would be the compression of the spring 23 which would absorb the forward movement of the plunger 25. Should the roll have been carried by the operator the least amount beyond the dead center line the pressure of the ram would have thrown the carrier to one side and finally brought it firmly against one of the stop screws 18 on the completion of the forward 105 stroke of the arm 8.

The operation of the glove turning machine with my improvements hereinbefore set forth incorporated therein, is, to all intents and purposes identical with that of my former glove turner, except in one very important particular. With the improved machine the operator need not concern himself in the matter of bringing the thumb support into accurate alignment with the plunger— 110

115

120

125

130

he merely throws the carrier either to one side or the other of the dead center line, or in approximate alignment, and places the glove over the supports.

5 Before the glove plungers engage the glove, the safety mechanism acts to complete the oscillation of the carrier and align the parts in perfect order.

Furthermore, should the operator, using 10 extreme care, position the carrier firmly against the stop, he is liable, in placing the glove on the supports, to accidentally move it slightly therefrom. As before, the ram 20 functions as the safety element 15 to place the parts in proper register.

As I stated in my preamble, two glove thumb supports have heretofore been proposed for glove turning machines, but they have been applied as fixed elements and as 20 such located permanently in their respective positions close to the line of finger supports.

In placing a glove on the machine, an operator requires considerable space in which to work in drawing the back of the 25 glove downwardly over the finger supports. My construction allows of this as when the operative thumb support is in close and adjacent relation to the finger supports the other thumb support is at a sufficiently 30 spaced distance to present no obstruction to the operator's hand as he grasps the wrist of the glove and pulls it down over the finger supports.

It is obvious, therefore, that with the novel 35 features embodied in my improvements, a vast amount of time is saved and superior advantages provided in the matter of convenience to the operator in the placement of the gloves on the turning machine.

40 Having thus described my invention, what I claim is:

1. A glove-turning machine comprising in combination a column, a bracket fixed to said column, a bracket, superjacent said fixed 45 bracket, reciprocable on said column, two glove thumb plungers fixed in said reciprocable bracket, a bifurcated carrier pivotally secured on said fixed bracket, two glove thumb supports on said carrier, and 50 means to automatically align one only of said glove thumb supports with its respective and mating plunger on each downward stroke of said reciprocable bracket.

2. A glove-turning machine comprising in 55 combination a fixed bracket, a reciprocable bracket, two glove thumb plungers on said reciprocable bracket, a bifurcated carrier oscillatively mounted on said fixed bracket, two glove thumb supports adjustably secured 60 to said carrier, means to manually oscillate said carrier whereby mating pairs of the said respective thumb supports and plungers may be brought into relative alignment, singly and alternately, and means adapted to yieldingly hold said mating pairs against dis-

alignment during the operation of turning a glove.

3. A glove-turning machine comprising in combination a fixed bracket, a plurality of horizontally aligning glove finger supports 70 on said fixed bracket, a vertically movable bracket, two glove thumb plungers on said movable bracket, a bifurcated carrier oscillatively mounted on said fixed bracket, the bifurcations thereof adapted to straddle the 75 said line of finger supports, a glove thumb support secured in each of said bifurcations of said carrier, means to manually oscillate said carrier, and automatic means to yieldingly bring one of the respective thumb supports into vertical alignment with one of the 80 respective thumb plungers on each downward stroke of the said movable bracket.

4. A glove-turning machine comprising in combination a fixed bracket, a plurality of 85 horizontally aligning glove finger supports on said fixed bracket, a reciprocable bracket, two glove thumb plungers on said reciprocable bracket, a bifurcated carrier oscillatively mounted on said fixed bracket, the 90 bifurcations thereof straddling the said line of finger supports, a glove thumb support secured to each of the said bifurcations, the center distance between the said supports being greater than the distance between the 95 two said thumb plungers, means to manually actuate said carrier, two movement-limiting stops on said fixed bracket, one on each side of the line of said finger supports, and means whereby a yielding pressure may be applied 100 to said carrier tending to force either one or the other of the said bifurcations into engagement with one of the respective stops.

5. A glove-turning machine comprising in combination a fixed bracket, a plurality of glove finger supports thereon, a vertically movable bracket, a plurality of glove finger and a plurality of glove thumb supports depending therefrom, a bifurcated oscillative carrier pivotally mounted on said fixed 110 bracket, the arms of said carrier disposed astride of the horizontal line through the plurality of finger supports, a glove thumb support on each of said arms, a roll pivotally mounted near the apex end of said carrier, 115 its axis being vertical, a ram having a wedge-shaped end engaging said roll, means whereby a yielding pressure against said ram in the direction of said roll may be applied at each downward stroke of said movable 120 bracket, and means to manually actuate said carrier.

6. A glove-turning machine comprising in combination a column, a fixed bracket on said column, a plurality of horizontally 125 aligned glove finger supports on said fixed bracket, a bifurcated carrier oscillatively mounted on said fixed bracket, the bifurcations thereof being disposed astride of a vertical plane cutting the centers of all of said 130

finger supports, a glove thumb support on each of said bifurcations, a movable bracket, two glove thumb plungers depending from said movable bracket and spaced, relatively, at a less center to center distance than the
5 two glove thumb supports on said carrier, a roll, having its axis vertically disposed, journaled on and near the apex of said carrier, a bearing, a ram slidable in said bearing, said ram having a wedge-shaped forward
10 end adapted to engage said roll, a plunger reciprocable in said ram and having a portion projecting outwardly from and rearwardly of said ram, a spring interposed between said plunger and said ram, an arm
15 pivotally attached to said column, its lower end engaging said plunger, and a bar adapted to intermittently engage said arm whereby a pressure may be applied thereto to yieldingly force said ram against said roll.
20 In testimony whereof I affix my signature.

DAVID BAUM.
